SHOEMAKING MACHINE

Otto Michalk, Dresden, Germany; Martha Johanna Elisabeth Michalk, nee Voigt, Dresden, and Hans Joachim Michalk, Chemnitz, Germany, heirs of Paul Otto Michalk, deceased

Application March 19, 1936, Serial No. 69,639
In Germany March 27, 1935

6 Claims. (Cl. 12—37)

This invention relates to shoe making machines and more particularly to a gluing machine.

An object of this invention is to provide a gluing press of the rotary type which is at all times under the control of the operator and which is so constructed that a relatively rapid drying adhesive may be used in the gluing process.

Another object of this invention is to provide a gluing press which is adapted to place the desired pressure on the part of the shoe being glued and to release the pressure as the device rotates on a standard.

With the foregoing and other objects in view, the invention will be more fully described hereinafter, and will be more particularly pointed out in the claims appended hereto.

In the drawings, wherein like symbols refer to like or corresponding parts throughout the several views;

20 Figure 1 is a fragmentary perspective view of a shoe gluing press constructed according to an embodiment of this invention.

Figure 2 is a fragmentary side elevation of the press carrying wheel and showing the drive means for the wheel.

Figure 3 is an enlarged sectional view through the coupling gear system for the driving means.

Figure 4 is a fragmentary top plan of the coupling gear system.

30 Figure 5 is a fragmentary perspective view of the pressing devices and showing the manner in which the pressing devices are progressively released.

Figure 6 is a perspective view partly broken away of one of the presses in operative position.

Referring to the drawings, the numeral 8 designates a standard or base having a press carrying wheel 1' rotatably mounted thereon. This wheel 1' is mounted for vertical rotation and is provided on the periphery thereof with a plurality of spaced apart driving teeth 1. The teeth 1 are adapted to engage a chain 28 which is trained over sprockets 28' and 28'' and which constitutes the driver for the press carrying wheel 1'.

The sprocket 28' is loose on a shaft 26' and at one side thereof is provided with one portion of a clutch for engagement with a complementary clutch means carried by a cam member 3 which is mounted on the shaft 26'. The cam 3 has a grooved collar 2 on the side thereof opposite from the clutch secured thereto and a spring constantly urges the cam 3 into clutching engagement with the clutch portion carried by the sprocket 28'. A worm drive 26 rotates the shaft

26' and a pulley 25 is connected to the worm drive 26 and is connected to a suitable source of power supply as shown in Figure 1.

A bell crank 2' has one portion thereof disposed in the groove of the collar 2 and the other arm 2'' of this bell crank is connected by means of a rod 6' to a releasing lever 6 which is rockably carried by the base or standard 8. The releasing foot lever 6 may be held in depressed position by means of a pawl carried by a second lever 6''.

The driving pulley 25 has associated therewith a friction clutch means 24 which is operated by means of a coupling lever 23. This lever 23 has an arm thereof disposed in the path of a lever 22 which contacts with the cam 3 being biased toward the cam 3 by a spring 27. The lever 22 is connected to a foot lever 4 by means of a connecting rod 4'' so that the lever 22 may be swung to a released position and, at the same time, move the lever 23 to a position to uncouple the clutch 24.

The press carrying wheel 1' has a plurality of fixed clamping or base members 5 secured thereto in spaced apart relation and in outstanding relation to the side of the wheel 1'. A pressure lever 12 is rockably carried by the support 40 extending upwardly from the base 5 and has a movable clamping or form member 5' secured thereto as by a yoke member 12'. The lever 12 on its upper side has a ratchet 15 which is engaged by a pawl member 14 mounted on a rocking arm 21. A spring 16 constantly pulls the pawl 14 into engagement with the teeth of the ratchet 15. The spring 16 has its inner end secured to a ring 29' carried by the wheel 1'. A U-shaped bar 30 is carried by the base 5 adjacent the inner end thereof and a spring 20 is interposed between the bight of the U-shaped member 30 and the upper side of the lever 12 adjacent the inner end of this lever. The spring 20 constantly urges the lever 12 to a released position. A pressure cylinder 10 is carried by the base 8 and is provided with a plunger 11 carrying a roller 13 which is adapted to engage the underside of the inner portion of the lever 12 so as to lower the form 5' and thereby press the work together.

The pressure cylinder 10 is connected to a suitable source of pressure, such as air pressure, and a valve is interposed in the pipe line connected to the cylinder 10 and is opened or closed by rocking of a lever or treadle 4'. A locking member 9 may be moved laterally to engage the lever or treadle 4' so as to hold the valve in open position. A second valve 8'' is also interposed in a pipe line

18' connected to a press releasing cylinder 18 mounted on the standard 8. The cylinder 18 has a plunger 17 slidable therein carrying a plate or disk 17' which is adapted to engage the inner 5 end of a pawl releasing rod 19 which is secured to the upper end of the pawl carrying lever 21. The rod 19 is slidable through the inner ring 29' carried by the wheel 1'.

The inner end of the form member 5 is secured 10 to a ring member 29 secured for movement with the wheel 1'. The pressure cylinder 18 with the releasing disk 17' is disposed laterally of the plunger 11 operated in the cylinder 10 so that after pressure has been applied to the movable 15 form 5' by means of the plunger 11 engaging the pressure lever 12 and the wheel 1' rotates for substantially a complete turn the releasing cylinder 18 releases the pawl 14 from the ratchet 15 through the releasing rod 19.

20 In the use and operation of this device, the work is inserted on the base form 5 and then the pressure lever 4' is pressed down so as to open the valve to the pressure cylinder 10. The plunger 11 will then rise and contact with the inner end 25 of the pressure lever 12 and lower the movable form 5' for contact with the material. As the outer end of the lever 12 is lowered the pawl 14 rides over the ratchet 15 so that when the pressure of the cylinder 10 is released the movable 30 form 5' will be held by the pawl 14 in operative position.

At the same time that the plunger 11 is rising the valve to the releasing pressure cylinder 18 is opened and the next or preceding press disposed 35 in confronting position to the disk 17' is released by outward movement of the plunger 17 which engages the press releasing rod 19. The disk 17' and the plunger 11 are disposed in different vertical planes, and when the press disposed on the 40 approach side of the disk 17' confronts this disk, the operation of this disk 17' will effect release of the press so that the material may be removed therefrom.

After this operation the lever 4 may be pressed 45 down and downward movement of the lever 4 will release the lever holding pawl 9 so that the treadle or lever 4' may rise to a released position. Downward movement of the lever 4 will effect coupling of the clutch 24 through the lever 23 so 50 as to effect movement of the wheel operating chain 28. As the chain 28 moves through the driving shaft 26' the cam portion of the member 3 will engage the lever 22 and move the drive clutch operating lever 23 into released position 55 in which position the form member 5 will be moved into a position where the releasing rod 19 will then be disposed in confronting position to the press releasing member 17-17'.

It will be apparent from the foregoing that a 60 gluing press has been disclosed which is capable of using adhesives capable of relatively quick drying and the number of presses carried by the wheel 1' may be varied to suit the particular quality of adhesive which is being used.

65 What is claimed is:

1. A shoe gluing press comprising a frame, a rotatable wheel carried by said frame, a plurality of circumferentially spaced apart press members carried by said wheel, each press member including a fixed clamping member, a movable clamping member, a rockable pressure lever carried by said fixed clamping member and having one end thereof secured to said movable clamping member, means engaging the lever intermediate the 70 ends thereof for rockably supporting the lever on

said fixed clamping member, a ratchet carried by said lever, a pawl engageable with said ratchet, means for swingably supporting said pawl from said fixed clamping member, a spring constantly holding said pawl and the supporting means therefor in operative position, means arranged on said frame engageable with said lever for moving said movable clamping member to clamping position, and means also arranged on said frame disposed laterally of said latter means 10 for releasing said pawl.

2. A shoe gluing press comprising a frame, a rotatable wheel carried by said frame, a plurality of circumferentially spaced apart press members carried by said wheel, each press member including a fixed clamping member, a movable clamping member, a rockable pressure lever carried by said fixed clamping member and having one end thereof secured to said movable clamping member, means engaging the lever intermediate the 20 ends thereof for rockably supporting the lever on said fixed clamping member, a ratchet carried by said lever, a pawl engageable with said ratchet, means for swingably supporting said pawl from said fixed clamping member, a spring constantly holding said pawl and the supporting means therefor in operative position, means engageable with said lever for moving said movable clamping member to clamping position, means disposed laterally of said latter means for releasing said 30 pawl, and means for rotating said wheel to a position to effect engagement of said pawl releasing means with a pawl.

3. A shoe gluing press comprising a rotatable wheel, a plurality of circumferentially spaced apart press members carried by said wheel, each press member including a fixed clamping member, a movable clamping member, a rockable pressure lever carried by said fixed clamping member and having one end thereof secured to 40 said movable clamping member, means engaging the lever intermediate its ends for rockably supporting the lever on said fixed clamping member, a ratchet carried by said lever, a pawl engageable with said ratchet, means for swingably supporting said pawl from said fixed clamping member, a spring constantly holding said pawl and the supporting means therefor in operative position, a releasing rod secured to said pawl and supporting means, means engageable with said lever for 50 moving said movable clamping member to clamping position, and pawl releasing means including a plunger movable to engage said releasing rod.

4. A shoe gluing press comprising a frame, a rotatable wheel carried by said frame, a plurality of circumferentially spaced apart press members carried by said wheel, each press member including a fixed clamping member, a movable clamping member, a rockable pressure lever carried by said fixed clamping member and having one end thereof secured to said movable clamping member, means for rockably supporting said lever to thereby carry said movable clamping member to clamping position, a ratchet fixed to said lever, a pawl engageable with said ratchet, means supporting said pawl for releasable engagement with said ratchet, a releasing member connected to said pawl and slidably engaging said wheel, operating means for said releasing member carried by said frame, and yieldable means for moving 60 said lever to released position upon movement of said pawl to released position.

5. A shoe gluing press comprising a frame, a rotatable wheel carried by said frame, means for rotating said wheel intermittently step by step, 7

5 a plurality of circumferentially spaced apart press members carried by said wheel, each press member including a fixed clamping member, a movable clamping member, a rockable press lever carried by said fixed clamping member and having one end thereof secured to said movable clamping member, means for rocking said lever to thereby carry said movable clamping member to clamping position, spring-pressed releasable holding means for holding said lever in clamping position, a slideable rod carried by said wheel connected to said holding means, and a stationary operating means disposed in a position for engagement with said rod to move said holding means to released position at a point preceding the movement of a clamping means to clamping position by said first operating means.

10 6. A shoe gluing press comprising a rotatable wheel, supporting means for said wheel, means for rotating said wheel intermittently step by step, a plurality of circumferentially spaced apart press members carried by said wheel, each press

15 member including a fixed clamping member, a movable clamping member, a rockable pressure lever carried by said fixed clamping member and secured at one end to said movable clamping member, means normally biasing said lever to released position, the opposite end of said lever projecting laterally of one side of said wheel, stationary lever operating means disposed in a position for engagement with said opposite end of said lever to rock said lever to clamping position, spring-pressed holding means for said lever, a releasing member connected to said holding means and having a portion projecting laterally of said wheel, and a stationary operating means carried by said supporting means disposed in a position for engagement with said projecting portion of said releasing member, said latter operating means being disposed laterally of said first operating means whereby to release said clamping means at a point preceding said first operating means.

20 OTTO MICHALK.
